UNITED STATES PATENT OFFICE.

ERNEST G. JOHNSON, OF BOSTON, MASSACHUSETTS, ASSIGNEE, BY MESNE ASSIGNMENTS, TO THE PALMER ELECTRIC AND MANUFACTURING COMPANY, OF CAMBRIDGE, MASSACHUSETTS, A CORPORATION OF MAINE.

RELAY.

Application filed December 30, 1922. Serial No. 609,896.

This invention relates to relays more particularly intended for controlling circuits in response to changes in energy conditions of the relay circuits which may or may not be derived from the controlled circuits. For this purpose the relay of the present invention is provided with a member movable in response to energy changes in the relay circuit and subjected at certain positions only 5 to other forces modifying the movement otherwise imparted to the member by such energy changes.

The invention is herein exemplified in a relay constructed to open a circuit on both 10 the rise and fall of voltage of the relay circuit to predetermined values, the other forces above mentioned acting to effect a quick opening and closing of the controlled circuit and to prevent the closing of the 15 controlled circuit after it has been opened, except at a predetermined voltage change from the high or low circuit opening values toward an intermediate value. This latter 20 effectually prevents fluttering or hunting 25 of the circuit closer because of slight rapid fluctuations in the voltage of the relay circuit. The controlled circuit may, if desired, be employed to impart correcting influences 30 for regulating and maintaining closely at a desired value the voltage of a lighting or power main circuit, or it may be desired to utilize the controlled circuit only when its 35 voltage lies within a desired limited range, the energy conditions of the relay circuit 40 being made responsive in the first instance to the voltage of the lighting or power circuit and in the second instance to that of the controlled circuit.

Other valuable uses of this relay will suggest themselves to those skilled in the art.

For a more complete understanding of this invention, reference may be had to the accompanying drawings in which

Figure 1 is a side elevation of a relay embodying the invention.

Figure 2 is a front elevation of the same.

Figure 3 is a fragmentary detail.

Figures 4 and 5 are fragmentary front elevations showing the switch for the controlled circuit opened by too high and too 50 low voltage respectively.

Figure 6 is a diagram showing the electrical circuits.

Referring to Figure 6, 1 represents a motor designed to be operated by a controlled circuit and only when the voltage of this circuit lies within predetermined limits, this being one exemplification of the utility of this invention. As shown one of the motor terminals connects through a wire 55 2 to one side of a source of power 3 and the other terminals of the motor connects through a normally open switch 4 to the opposite side of the source of power. The switch 4 may be held closed by the circuit 60 controlled by the relay, a solenoid 5 being indicated diagrammatically for this purpose in a circuit also deriving energy from the source of power 3 and controlled by a switch indicated at *a*. This switch comprises a 65 fixed contact 6 and a movable contact 7, the contact 7 being normally biased to closed position as by means of its weight. It is evident then that when the switch *a* is closed the switch 4 is also closed and the motor 70 circuit is closed. Should the switch *a* open, however, the motor circuit is immediately opened by the switch 4. The opening of the switch *a* is controlled by a relay circuit 75 which as shown also derives its energy from the source of power 3 and has therein a solenoid 10.

Referring now to Figures 1 and 5 the solenoid 10 is shown as fixed in vertical position to a base or panel board 11 and has 80 slidably therein a magnetic core 12 the weight of the core tending to draw it out of the solenoid. To eliminate any sticking or frictional drag between the core 12 and the solenoid, guide rods 13 are shown as 85 projecting downwardly from the solenoid and the lower end of the core has fixed thereto a guide bar 14 engaging these rods and to which is fixed an outwardly extending angle piece 15. The switch arm 7 has 90 adjustably fixed therein a screw 16 which is adapted to be struck by the angle member 15 when the core 12 is raised sufficiently within the solenoid, thus to raise the arm 7 and open the switch *a*. The arm 7 also has 95 fixed thereto an adjustable screw abutment 17 which rests upon a lever arm 18 ful-

crumpled at 19, this fulcrum as shown being carried by a U shaped member 20 fixed to the outer end of a bracket arm 21 attached to the forward face of the panel board 11. 5 At the opposite side of the fulcrum 19 from the abutment 17 the lever arm 18 carries a screw 25 the upper end of which may be struck by the angle member 15 on the descent of the core 12, so that the arm 18 may 10 be rocked and the abutment member 17 raised causing the switch element to be raised and its contact with the member 6 broken.

It is well known that solenoids may be 15 so designed that their cores may float therein and if biased to move outwardly thereof to be moved definite distances by definite changes of voltage imposed on the solenoid. Hence the position of the core 12 within 20 the solenoid is dependent upon the energy impressed on the solenoid so that should the energy approach a sufficiently high value, the core will be raised sufficiently to open the switch *a*, or if the energy falls 25 to a predetermined point the core 12 is permitted to fall sufficiently to open the switch *a*. As shown the arm 7 of the switch is counterweighted by the weight 30 and an adjustable stop screw 31 is provided to limit 30 the opening movement of this arm.

Should the construction above outlined be employed without modification for opening or closing the switch *a* it is evident that the switch would be opened at the attainment of 35 a certain definite voltage in the solenoid, but should this voltage fall a very small amount, the switch would be allowed to close again. Thus if small energy changes were impressed on the solenoid, the switch 7 40 would be caused to open and close rapidly, thus causing a fluttering action of the entire mechanism and causing the motor 1 to be energized and deenergized rapidly. Under such conditions this motor would be liable 45 to be damaged. In order to prevent such a fluttering or hunting action and further in order to relieve the normal force of the solenoid on the core 12 from the duty of opening the switch, the following mechanism 50 has been provided.

Within the upper end of the solenoid is 55 adjustably positioned a stopper 40 of magnetic material. This may be adjustably fixed in vertical position by means of a set screw 41, threaded in a block 42 fixed to the panel 11. This stopper has an opening 60 for the slidable reception of a guide rod 43 of non-magnetic material fixed within the upper end of the core 12. This holds the upper end of the core out of engagement 65 with the inner face of the solenoid coil, thus preventing it from catching thereon or being frictionally retarded thereby. This stopper is so adjusted vertically in the solenoid that immediately before the core

reaches its upper position at which the switch 7 is to be opened, it comes within the magnetic field of the stopper 40 caused by the energy imposed on the solenoid. When this takes place, this magnetic field effects 70 a sudden upward impulse to the core 12, imparting thereto a force to cause the angle piece 15 to strike sharply against the screw 16 and open the switch arm. The stop screw 31 and the stopper 40 are so adjusted that 75 the core 12 may not actually contact the lower end of the stopper 40 and the air gap between the stopper and the core may be determined as desired. This relative position of the core and stopper when the switch 80 *a* is in open position is illustrated in Figure 4. This construction not only insures an additional force being imparted to effect the opening of the switch *a*, but also causes a 85 holding effect to be imparted to the core to retain it at its upper limit of motion until the energy imparted to the solenoid has decreased to a value somewhat below that required to bring it initially into the field of 90 force of the stopper. When this condition occurs the core drops away suddenly permitting the switch *a* to close quickly. The amount of the air gap between the stopper and the core determines the amount to which 95 the energy impressed on the solenoid must be reduced after the switch *a* has been opened by the movement of the core 12 to its upward limit of motion before this core can descend due to its weight, and permit the 100 switch *a* to close.

Likewise when the switch is opened by the falling of the core on a predetermined decrease in the energy impressed on the solenoid, means is provided for imparting an additional force to the solenoid for opening the switch *a* and for holding it open until energy impressed on the solenoid is raised to a point above that at which the switch is opened. For this purpose the bracket 21, beforementioned, has adjustably threaded 105 therein a plug or block 45 of magnetic material (see particularly Figure 3) so that as the core descends, due to a decrease of energy in the solenoid, it approaches the upper end of the block 45, which thereupon becomes magnetized from the lines of force 110 extending from the lower end of the core. As this block 45 is held stationary this magnetic force immediately results in a downward pull against the core 12 so that the angle member 15 impinges on the screw 25 with a sudden blow and causes the switch arm 7 to be suddenly pushed upwardly to 115 open the switch *a*. Here again it is desirable to adjust the air gap between the lower end of the core 12 and the plug or block 45 and for this purpose a nonmagnetic abutment screw 46 is threaded therethrough and against the upper end of which the core 12 120 impinges. The adjustment of this screw 125

determines the air gap and therefore determines the increase of energy which must be imparted to the solenoid to cause the core 12 to be separated from the field of influence of the plug 45 so as to be raised quickly into position to permit the switch *a* to close. To hold the plug 45 in adjusted position its lower end may have threaded thereon a lock nut 47.

10 It will be seen that the force imposed by the magnetized plug at the upper end of the solenoid acts on the core in the same direction as an increased energization of the solenoid and that the force imposed by the magnetization of the lower block 45 acts in opposition to the energization of the solenoid or in the same direction as a decreased energization thereof.

Having thus described an embodiment of this invention it should be evident that many changes and modifications may be made therein without departing from its spirit or scope as defined by the appended claims.

25 I claim:

1. In an electrical relay, a contact member biased in one direction, a member movable in response to changes of energy conditions and operative at definite limits of motion to move said contact member out of its biased position, and means for imposing on said movable member when adjacent said limits of motion forces modifying its movement in response to said changes of energy conditions.

2. In combination, a normally closed contact member, a member movable in response to changes of energy condition in a circuit and operative at predetermined limits of its motion to open said contact member, and means for imposing on said member adjacent said limits forces acting with relation to the energy changes in said circuit to effect sudden movements of said member when adjacent said limits toward and from said limits.

3. In combination, a normally closed contact, a member movable in response to energy changes in a circuit and operative adjacent limits of its motion to open said contact, and means for causing the energy in said circuit to exert a drawing and holding effect on said member when adjacent said limits toward the respective limits.

4. In combination, a member movable in response to energy changes in a circuit between determined limits, means for causing energy in said circuit to exert a drawing and holding effect on said member when adjacent either of said limits toward the respective limits, and a device actuated by the movement of said member only when adjacent to said limits.

5. In an electrical relay, a normally closed switch, a member responsive to energy

changes acting to open said switch at determined maximum and minimum energy values, and means acting to prevent the closing of said switch except when said energy shall have reached definite values different from and intermediate to said opening values.

6. In a device of the class described, a device normally biased to one condition, a member responsive to energy changes acting to operate said device from said condition at determined maximum and minimum energy values, and means for preventing the return of said device to its normal condition until the energy shall have reached values of determined differences from and intermediate of said maximum and minimum.

7. A relay comprising a switch normally biased to closed position, electromagnetic means for opening said switch at determined maximum and minimum energization, and means for preventing the closing of said switch until the energization shall have reached one or the other of values intermediate of and at predetermined differences from said maximum and minimum.

8. A relay comprising a switch normally biased to closed position, a solenoid, a magnetic core movable in said solenoid and normally biased away from the center thereof to be movable in opposite directions between limits by energy changes in said solenoid between determined high and low values, means for effecting the opening of said switch on movement of said core to either of its limits, and magnetic material fixed beyond the ends of said core and within the limits of the magnetic field at the corresponding end when said core is adjacent its limit of motion in either direction.

9. A relay comprising a switch normally biased to closed position, an upright solenoid, a core vertically movable in said solenoid to be drawn upwardly therein when said solenoid is sufficiently energized and to fall therefrom when the energy falls, means for opening said switch when said core rises to a predetermined extent, means for opening said switch when said core falls to a predetermined extent, a magnetic element in said solenoid into the field of force of which the upper end of said core moves as it approaches its upper limit of motion, and an element of magnetic material fixed beneath the lower end of said core and within the magnetic field of said core as said core approaches its lower limit of motion.

10. A relay comprising a switch normally biased to closed position, an upright solenoid, a core vertically movable in said solenoid to be drawn upwardly therein when said solenoid is sufficiently energized and to fall therefrom when the energy falls, means for opening said switch when said core rises to a predetermined extent, means for opening said switch when said core falls to a predetermined extent.

- terminated extent, a magnetic element in said solenoid into the field of force of which the upper end of said core moves as it approaches its upper limit of motion, and an element of 5 magnetic material fixed beneath the lower end of said core and within the magnetic field of said core as said core approaches its

lower limit of motion, and means for adjusting the air gaps between said core and said elements at the limits of motion of said core. 10

In testimony whereof I have affixed my signature.

ERNEST G. JOHNSON.
